UNITED STATES PATENT OFFICE

HYMAN R. SEGAL, OF NEW YORK, N. Y.

WINDOW SHADE

Application filed June 12, 1931. Serial No. 543,834.

This invention relates to an improvement in window shades and, more particularly, to a device which can be readily attached to a window shade and thereby improve the operation of the latter.

It is a common experience that window shades of the type supported on spring tensioned rollers have a tendency to overwind if they are raised too suddenly or if the person raising the shade should release his grasp of the same and allow it to run up the window unchecked. This results in a winding and tangling of the pull cord about the shade roller and in many instances in a complete unwinding of the shade roller spring, as well as being accompanied by considerable noise and confusion.

It is also a frequent occurrence that when a window is opened from the top, the window shade will be sucked outward by a draft of air and be caused to flap and flutter in the wind. This, of course, puts considerable strain on the shade fabric and if continued would soon cause the shade to tear and wear out.

It is an object of the invention to provide a window shade in which the possibility of such overwinding is completely eliminated and in which the stopping of the shade is cushioned so as to prevent undue strain on the parts.

It is also an object of the invention to provide a window shade in which the danger of the shade being drawn outwardly when the window is open from the top is done away with.

It is a further object of the invention to provide a device for attachment to window shades, which device may be readily and simply applied without altering the shade and which will be durable and serve over long periods of time without attention.

Another object of the invention is to provide a device of the character described which may be readily detached from the window shade when it is desired to clean or replace the latter, and which may be again applied after these operations have been performed.

A still further object of the invention is

that of furnishing a window shade which is simple and rugged in construction and which may be manufactured at relatively nominal cost and will function over long periods of time with freedom from wear or other difficulty.

With these and other objects in mind, reference is had to the attached sheet of drawing illustrating a practical embodiment of the invention and in which:

Fig. 1 is a front elevation of a window frame with a shade of the improved type in lowered position;

Fig. 2 is a side view in cross section of a window frame with the shade in raised position;

Fig. 3 is an enlarged plan view of the lower corner of the shade shown in Fig. 1 with a slightly modified device in place;

Fig. 4 is an enlarged cross section of a lower corner of the shade shown in Fig. 1, and

Fig. 5 is a cross section of the lower edge of a window shade showing another form of the invention attached thereto.

In the several views, the numeral 6 indicates a window frame of any conventional type, in which a window shade 7 is supported as at 8. The shade is provided with a bottom hem portion 9 in which is carried the conventional shade stick 10. Through the bottom shade hem and stick is inserted a pull cord 11, by means of which the shade may be raised or lowered.

It is proposed that the preferred type of shade be provided with side hems 12 which extend for the full length of the shade. In these side hem-portions, stiffening or resilient members 13 are inserted rather than fastening them to the outer surface of the shade. These stiffeners may be made of any desired material such as wood, metal, fibre, whalebone, or the like, and are of a less width than the side hem portions of the shade. The members may be cut in sections of any desired length, the length of such members being determined by the height to which it is desired to raise the shade as hereinafter brought out.

With these members in place, a person desiring to raise the shade would grip the pull

cord and pull the shade downward to a slight degree so as to release the ratchet which is associated with the roller, and thereafter the tension of the roller spring would cause the shade to wind about the roller and travel upwardly with respect to the window frame. As soon as the stiffeners reach the position shown in Fig. 2, they would jam against the upper bar of the window frame and a further winding of the shade would become impossible. It is, therefore, obvious that should the operator of the window shade lose his grasp on the pull cord and allow the shade to travel up the window unchecked, it would stop as soon as the stiffeners came in contact with the upper bar of the window frame. In this manner it would be possible by the addition of supplementary or additional stiffeners, such as 13', to predetermine the exact distance that the shade could be raised so that, for example, if stiffener sections were inserted in the shade hems for a distance equal to half the window length, it would be possible to raise the shade only half way up the window.

With a view to removing the stiffeners from the shade in order to clean the latter or possibly with a view to replacing the stiffener in a new shade, the shade has been provided with a slit 14 in the lower edge of the bottom hem which slit extends inwardly at each end of said lower end for a distance equal to the width of the side hems. It is, therefore, possible by simply pulling the shade stick sideways to first remove the stiffeners from one side hem and then by pulling the shade stick sideways in the other direction to remove the stiffeners from the other side hem.

In the embodiment shown in Fig. 3, stiffeners 15 are provided which stiffeners are of no greater length than the width of the bottom shade hem. When employing stiffeners of this type, it would be possible to remove them from the shade simply by pulling the shade stick to one side and allowing the stiffeners to drop one by one into that part of the bottom hem formerly occupied by the shade stick and thereafter removing them one at a time from the side of the shade. This would do away with the necessity of providing a slit in the bottom edge of the bottom shade hem. If it is desired to limit the extent to which stiffeners should be inserted in the side hems, stitching 16 can be provided which will seal the side hems to prevent the stiffeners from being inserted beyond that point.

Some shades, especially the cheaper variety, are not provided with side hems. With this in mind, the embodiment shown in Fig. 5 has been provided. In this instance a resilient member 17 is embedded in a wedge shaped body 18 which may be formed from rubber or any other suitable material and the completed device is pressed or snapped over the bottom edge of the shade and stick

so that it takes a position entirely encircling the same. By positioning one of such devices in the center of the bottom edge of the shade or at either end of the same, it is apparent that when the shade reaches the raised position, the member 18 will wedge between the bottom edge of the upper bar of the window frame and the top of the shade roller, thus preventing the further winding of the shade.

It is further apparent that this device might be formed of a material inherently resilient in itself so as to make the insertion of the resilient member 17 unnecessary. Additionally, by the modification of the shape of this member so as to cause it to extend upwardly along both the inner and outer shade surfaces, it would be possible to effect an arresting of the upward movement of the shade at a position corresponding to the length of the member. Thus, the winding of the shade could be limited to half the height of the window or any other predetermined distance.

From the foregoing it will be appreciated that, among others, the several objects specifically aforementioned are achieved. It is intended, however, that numerous changes in construction and rearrangement of parts might be resorted to without departing from the spirit of the invention as defined in the claims.

Having described my invention, what I claim as new and desire to secure by Letters Patent is:

1. As an article of manufacture, a window shade comprising a body of flexible material, a hem extending across the bottom edge of said shade, a shade stick disposed within said hem, additional hems extending along each side of said shade and relatively non-flexible members disposed within said side hems adjacent said bottom hem.

2. A device for association with a window shade formed with a side hem comprising a stiffener for insertion within said side hem and adapted to limit the movement of the shade when the latter is in place in a window frame.

3. A window shade of the spring roller type including a shade body having a side hem, a bottom hem formed in said body, a shade stick disposed within said bottom hem, and one or more stiffeners carried by said body and maintained in position by said stick and side hem.

4. A window shade of the spring roller type including a shade body, a bottom hem formed in said body, a shade stick disposed within said hem, side hems formed in said shade body, and one or more non-flexible stiffeners disposed within said side hems and adapted to limit the movement of said shade when the latter is in place in a window frame.

5. A window shade of the spring roller type comprising a shade body, side hem por-

tions formed in said body, a bottom hem formed in said body, means of access to said side hem portions being provided through said bottom hem portion, and additional means for cooperation with said bottom hem portion to render said side hem portions inaccessible.

5 6. A window shade of the spring roller type, including a shade body formed with side hem portions, an additional hem formed in the bottom of said shade body, access to the interior of said side hem portions being made through said bottom hem, a shade stick for cooperation with said bottom hem and normally closing the entrance to said side hem interiors, and stiffening members for insertion inside said side hem portions when said shade stick is displaced and adapted to be retained in position by the latter when the parts are in assembled relationship.

10 7. A device for association with the bottom edge of a window shade comprising a substantially wedge shaped member formed with a central slot and a U shaped spring element embedded in said member so as to press the side walls of said slot toward each other.

15 In testimony whereof I affix my signature.
